DUPLICATING APPARATUS

Wilhelm Ritterfeld, Berlin, Germany

Application September 6, 1935, Serial No. 39,378
In Germany September 7, 1934

16 Claims. (CL 101—132)

The present invention relates to a duplicating apparatus and, more particularly, to an apparatus for printing records from a copyable mirror-script original onto a continuous strip of paper.

5 It is an object of the present invention to provide a duplicating apparatus which is simple and efficient and which produces prints onto a continuous strip of paper previously moistened with a rapidly volatilizing solvent and from a 10 copyable mirror-script original.

It is another object of the present invention to provide a duplicating apparatus which is adapted to print onto a continuous strip of paper and is adapted to cut this strip of paper into individual 15 printed sheet of adjustable length.

A further object of the invention is an apparatus for multiplying records which is easily adaptable for handling printing drums of different dimensions for printing onto sheets of various 20 length cut from a continuous strip of paper immediately after the printing.

The present invention also contemplates a duplicating apparatus which is adaptable both for printing onto single sheets of paper and onto 25 a continuous strip of paper and which can be changed over easily and at will from one manner of operation to the other.

Other and further objects and advantages of the invention will appear from the following description taken in conjunction with the accompanying drawings, in which:—

Fig. 1 is a side elevational view, somewhat fragmentary, of a duplicating apparatus embodying the principles of the present invention; 30 Fig. 2 illustrates a fragmentary and sectional view of the driving gears in a duplicating apparatus illustrated in Fig. 1.

Fig. 3 depicts a vertical sectional view of lever 26 shown in Fig. 2.

40 Generally speaking, according to the principles of my invention I provide a feed roll containing the continuous strip of paper, a moistening device for moistening this strip of paper with a rapidly volatilizing solvent, a printing drum bearing the copyable mirror-script original and cooperating with a counter pressure roller. An automatic cutting device for the paper strip is provided and arranged behind the printing drum and dependent thereupon. This cutting device is 45 adapted to cut the continuous strip of paper into individual parts or sheets the length of which is adjustable. I prefer to arrange the cutting device immediately behind the printing drum pulling the continuous strip of paper from 50 the feed roll so that the continuous strip of

paper is conveyed to the cutting device exclusively by means of the printing drum and the counter pressure roller. It is desirable to arrange the feed roll as an adjustable unit in order to align the continuous strip of paper. The cutting device essentially comprises one knife or a plurality of knives rotatively arranged around an axle and cooperating with a stationary knife, resiliently and adjustably secured to the machine frame. The rotatable knives are at a 5 distance from their axle sufficient to provide for free passage of the printed paper between axle and knife. To insure straight cutting of the continuous paper strip during its motion I arrange the cutting edges of the movable or rotatable knives at an angle to their axle, this angle being capable of adjustment according to the speed of the paper strip or to other considerations. To change the cutting length, I provide a cam or the like driven from the printing drum 10 and which periodically pushes the stationary knife out of its working position or pushing the same back into its working position so that changing to different cutting lengths during 15 operation of the apparatus is effected by switching on or off the drive of the cam. In some cases, I also employ additional means of controlling or adjusting the movable or rotatable knives changing the position of the knives in 20 relation to the axle or to each other whereby the 25 cutting lengths may be regulated with great precision.

According to further principles of my invention I provide both means for continuously driving the printing drum and the cutting device as well as means for intermittently rotating the printing drum only. I employ a change gear or the like for operating one of these 30 means whereby it is possible either to print onto a continuous paper strip or onto sheets individually fed into the apparatus. Changing over to different methods of operation or to different cutting length is accomplished by means of one member, preferably by a lever that controls the change gear driving the printing drum, the 35 knife drum and also the cam controlling the stationary knife. When the duplicating apparatus embodying my invention is set to print onto single sheets the knife drum is held in a definite stationary position by an adjustable stop which 40 is automatically pushed aside by the knife drum when changing over to printing onto a continuous strip of paper. I arrange the counter pressure roller adjustably so that the printing drum 45 may be easily exchanged with other drums 50 55

of different size without changing the bearing of the drum. This makes it possible to use originals of widely different size and also to vary the cutting lengths. It is advantageous to have 5 also the feeding table easily removable. For controlling the feed of the rapidly volatilizing solvent I provide a cam of appropriate design cooperating with the moistening means which feed the solvent two or more times during each rotation 10 of the printing drum.

Referring now more particularly to Fig. 1 which depicts a duplicating apparatus embodying the principles of my invention, the reference character 1 designates a continuous strip of 15 paper wound on feed roll 2 which rests adjustably in lever 3 in order to make aligning of the paper strip possible. Over a guide roller 4 the continuous strip of paper is introduced between a printing drum 5 and a counter pressure roller 20 6 whereby the paper strip is pulled off the feed roll and over a short guide table 7 is conveyed to the cutting device arranged directly behind the printing drum.

The cutting device comprises movable or rotatable knives 8 and 9 which are secured at a distance on axle 10 in such manner that they may be adjusted if desired. The cutting edges of the knives are arranged at an angle to axle 10 which may be adjusted according to the feeding speed 30 of the continuous paper strip. The stationary knife 11 is secured to the end of a swivel lever 12 pulled by spring 13 against an adjustable stop 14 which permits exact adjustment of the cutting edge. This stationary knife can be made 35 temporarily inoperative by cam 16 slidably fastened on axle 15. If this cam rotating with the printing drum is slid in the direction of axle 15 to come into the plane of lever 18 pivoted in 40 it will strike this lever once for every revolution of the printing drum. In this moment both lever 18 and connecting link or lever 19 will be displaced the latter pulling the stationary knife 11 out of its working or operative position shown in the drawing. Of course, the 45 stationary knife will be returned in its former position by spring 13 as soon as cam 16 has passed.

The gearing between the printing drum and the rotatable knives is adjusted in such manner that stationary knife 11 will be pushed out 50 of its operative position by cam 16 in the same moment when one of the two rotatable knives 8 or 9 is passing the cutting edge of said stationary knife 11. This will have the result 55 that one of the rotatable knives will not cooperate with the stationary knife in cutting the continuous strip of paper. In this manner, sheets will be cut having twice the length of those cut when the stationary knife has been 60 cooperating with both rotatable knives.

Fig. 2 illustrates a preferred arrangement of the driving gears in my duplicating apparatus. Both spur gear 21 and a spur gear on segment 22 are rigidly connected to shaft 20. Between 65 these two gears is a loosely running chain wheel rigidly connected to ratchet wheel 23, the chain wheel being driven by a motor or the like.

On spur gear 21 is arranged a pawl 24 which is adapted to be thrown into ratchet wheel 23 70 by hand or foot motioned means thereby coupling the drive to shaft 20 and to spur gears 21 and 22 secured to said shaft. On the printing drum axle 15 is arranged a slideable bushing 25 which can be slid on said axle and held in certain positions by means of a notch sector con-

trolled lever 26. The broad spur gears 27 and 28 the spur gear of segment 29 and the cam 16 already described in connection with Fig. 1 are all rigidly fastened to bushing 25.

The operation of my duplicating apparatus 5 will readily be understood by those skilled in the art. In the position of the gears depicted in Fig. 2, spur gear 21 is driving gear 28 and therefore gear 27 which in turn drives axle 10 of the rotatable knives via connecting gears 30. Cam 16 is not in the plane of lever 18 and will pass same, leaving stationary knife 11 in its operative position all the time. Both of the rotative knives will cooperate with the stationary knife and thereby, for example, will cut the continuous 15 paper strip in sheets having half the size of the standard letter size.

When lever 26 is put over into the second notch position, bushing 25 will be slid to the left without changing the gearing conditions on 20 account of the broad spur gears 27 and 28. Cam 16, however, now comes in the plane of lever 18 and will cooperate with same turning away the stationary knife once for each revolution of the printing drum so that sheets of 25 double length will be cut.

In the third notch position spur gears 21 and 28 are not connected at all but instead of these the spur gears of segments 22 and 29 become connected and cause a turning of the drum at 30 intervals for printing on individual sheets fed into the apparatus by hand. In this position spur gears 21 and 30 become disconnected thereby making the knife drum and the rotatable knives inoperative. Instead of using the electric 35 drive the duplicating apparatus can also be driven by hand by means of a crank to be put on shaft 20. When feeding individual sheets by hand into the apparatus, a resilient stop 36 will hold the knife drum in a definite inoperative 40 position.

For printing on larger size sheets, the printing drum may be exchanged for a larger one. The exchanging operation is made possible by having the counter pressure roller 6 arranged 45 slidably and adjustably in a cut or slot 32. The feed table 33 is also easily removable. Cam 34 attached to the printing drum will lift the moistening device 35 when sheets are fed by hand at each revolution of the drum. Two 50 further cams 36 are provided for opening and closing valve 38 of tank 39 containing the rapidly volatilizing solvent twice during each revolution of the drum by means of rods 37.

Having now described the principles of my 55 invention and a preferred embodiment thereof, it is readily understood that many variations and modifications of my invention may be resorted to by those skilled in the art without departing from the true scope and spirit of my invention 60 as disclosed in the present specification and as defined in the appended claims.

I claim:-

1. Apparatus for printing records from a copyable mirror-script original onto a continuous 65 paper strip previously moistened with a rapidly volatilizing solvent comprising a printing drum bearing copyable mirror-script original, a counter pressure roller co-operating with said drum, means for passing a continuous paper strip, 70 moistened with a rapidly volatilizing solvent between said drum and said roller, at least one knife rotatably arranged on an axis, a displaceable stationary knife cooperating therewith and arranged adjustably and swingably in the ma- 75

chine frame for cutting said continuous strip of paper into adjustable lengths, and means for intermittently displacing said stationary knife from an operative into an inoperative position 5 to vary the cutting length.

2. Apparatus for printing records from a copyable mirror-script original onto a continuous paper strip previously moistened with a rapidly volatilizing solvent comprising a printing drum 10 bearing copyable mirror-script original, a counter pressure roller co-operating with said drum, means for passing a continuous paper strip moistened with a rapidly volatilizing solvent between said drum and said roller, a plurality of knives 15 rotatively arranged around an axle at sufficient distance therefrom to provide free passage for said paper strip between said knives and said axle, a displaceable stationary knife cooperating with said knives for cutting said continuous 20 paper strip into sheets of adjustable length, and means for intermittently displacing said stationary knife from an operative into an inoperative 25 position to vary the cutting length.

3. Apparatus for printing records from a copyable mirror-script original onto a continuous paper strip previously moistened with a rapidly volatilizing solvent comprising a printing drum 30 bearing copyable mirror-script original, a counter pressure roller co-operating with said drum, means for passing a continuous paper strip moistened with a rapidly volatilizing solvent between said drum and said roller, a plurality of knives 35 rotatably arranged around an axle and enclosing an adjustable angle therewith, a displaceable stationary knife resiliently and adjustably mounted in the machine frame co-operating with said rotatable knives for cutting said continuous strip of paper into individual sheets, and means 40 for intermittently displacing said stationary knife from an operative into an inoperative position for varying the length of said sheets.

4. Apparatus for printing records from a copyable mirror-script original onto a continuous paper strip previously moistened with a rapidly 45 volatilizing solvent comprising a machine frame, a printing drum bearing copyable mirror-script original mounted in said frame, a counter pressure roller co-operating with said drum, means for passing a continuous paper strip moistened 50 with a rapidly volatilizing solvent between said drum and said roller, a plurality of rotatable knives arranged around an axle and rotated in dependence on the printing drum, said rotatable knives being capable of adjustment of their 55 position in relation to each other and to said axle, and a stationary knife resiliently and adjustably mounted in the machine frame adapted to cooperate with said rotatable knives for cutting said continuous paper strip into individual sheets, said stationary knife capable of being 60 intermittently displaced from an operative into an inoperative position to vary the length of said individual sheets.

5. Apparatus for printing records from a copyable mirror-script original onto a continuous paper strip previously moistened with a rapidly volatilizing solvent comprising a machine frame, a printing drum bearing copyable mirror-script original mounted in said frame, a counter pressure roller co-operating with said drum, means for passing a continuous paper strip moistened 65 with a rapidly volatilizing solvent between said drum and said roller, a plurality of rotatable knives arranged around an axle, a displaceable stationary knife mounted in the machine frame

and capable of co-operation with said rotatable knives for cutting said paper strip, and a cam-like member driven in dependence on the printing drum and adapted to intermittently displace said stationary knife to make some of the rotatable knives inoperative whereby individual sheets of greater length will be cut. 5

6. Apparatus for printing records from a copyable mirror-script original onto a continuous paper strip previously moistened with a rapidly 10 volatilizing solvent comprising a printing drum bearing copyable mirror-script original, a counter pressure roller co-operating with said drum, means for passing a continuous paper strip moistened with a rapidly volatilizing solvent between said drum and said roller, a plurality of knives 15 rotatably arranged around an axle, a displaceable stationary knife mounted in the machine frame and capable of co-operation with said rotatable knives for cutting said paper strip, 20 a cam-like member adapted to intermittently displace said stationary knife to make some of the rotatable knives inoperative, and controlled driving means for said cam-like member to drive same in dependence on the printing drum whereby 25 said paper strip will be cut to individual sheets of one length if said cam is actuated by said driving means and said paper strip will be cut to pieces of greater length if said cam is not actuated by said driving means. 30

7. Apparatus for printing records from a copyable mirror-script original onto a continuous paper strip previously moistened with a rapidly volatilizing solvent comprising a printing drum bearing copyable mirror-script original, a counter 35 pressure roller co-operating with said drum, means for passing a continuous paper strip moistened with a rapidly volatilizing solvent between said drum and said roller, automatic cutting means including a displaceable stationary knife 40 and a plurality of rotatable knives for said paper strip, means for continuously driving said printing drum and said cutting means for printing onto a continuous paper strip, means for intermittently driving said printing drum to print 45 onto sheets fed into the apparatus individually, and means for selectively actuating one of said driving means.

8. Apparatus for printing records from a copyable mirror-script original onto a continuous 50 paper strip previously moistened with a rapidly volatilizing solvent comprising a printing drum bearing copyable mirror-script original, a counter pressure roller co-operating with said drum, means for passing a continuous paper strip capable 55 of being moistened with a rapidly volatilizing solvent between said drum and said roller, automatic means including a displaceable stationary knife and a plurality of rotatable knives for cutting said paper strip to sheets of adjustable length, means for continuously driving said printing drum and said cutting means for printing onto said continuous strip of paper, means for intermittently driving said printing drum to print 60 onto sheets fed into the apparatus individually, and a control member capable of selectively actuating said driving means and of controlling the length of the sheets cut by said cutting means. 65

9. Apparatus for printing records from a copyable mirror-script original onto a continuous paper strip previously moistened with a rapidly volatilizing solvent comprising a printing drum bearing copyable mirror-script original, a counter pressure roller co-operating with said drum,

- means for passing a continuous paper strip capable of being moistened with a rapidly volatilizing solvent between said drum and said roller, rotatable knives, a cam-controlled stationary 5 knife adapted to cooperate with said rotatable knives for cutting said paper strip to sheets of adjustable length, and a lever-controlled change gear for selectively driving said printing drum and said rotatable knives continuously for printing onto a continuous strip of paper and driving said printing drum intermittently for printing onto single sheets said control lever being capable of controlling the operation of the stationary knife actuated by said cam.
10. Apparatus for printing records from a copyable mirror-script original onto a continuous paper strip capable of being moistened with a rapidly volatilizing solvent comprising a printing drum bearing copyable mirror-script original, a counter pressure roller co-operating with said drum, means for passing a continuous paper strip moistened with a rapidly volatilizing solvent between said drum and said roller, rotatable knives and a stationary knife for cutting said 15 paper strip, means for continuously driving said printing drum and said rotatable knives, means for intermittently driving said printing drum, controlling means for selectively actuating said driving means, and a stop movably arranged in the apparatus frame to hold said rotatable knives in a predetermined inoperative position when the intermittent driving means are actuated.
11. Apparatus for printing records from a copyable mirror-script original onto a continuous paper strip comprising a printing drum bearing copyable mirror-script original, a counter pressure roller co-operating with said drum, means for passing a continuous paper strip moistened with a rapidly volatilizing solvent between said drum and said roller, rotatable knives and a stationary knife for cutting said paper strip, means for continuously driving said printing drum and said rotatable knives, means for intermittently driving said printing drum, controlling means for selectively actuating said driving means, and a stop movably arranged in the apparatus frame to hold said rotatable knives in a predetermined inoperative position when the intermittent driving means are actuated and adapted to be pushed aside by the rotatable knives when the continuous driving means are actuated.
12. Apparatus for printing records from a copyable mirror-script original onto a continuous paper strip previously moistened with a rapidly volatilizing solvent comprising a printing drum bearing copyable mirror-script original, a counter pressure roller co-operating with said drum, means for passing a continuous paper strip moistened with a rapidly volatilizing solvent between said drum and said roller, automatic cutting means including a displaceable stationary knife and a plurality of rotatable knives for said paper strip, and cam-controlled moistening means for said paper strip to release a rapidly volatilizing solvent twice during each revolution of the drum.
13. Apparatus for printing records from a copyable mirror-script original onto a paper sheet comprising a printing drum bearing copyable mirror-script original, a counter pressure roller co-operating with said drum, means for passing a paper sheet between said drum and said roller, automatic cutting means including a displaceable stationary knife and a plurality of rotatable knives for said paper sheet, a moistening device for moistening said paper sheet with a rapidly volatilizing solvent, and means for periodically and automatically feeding said solvent to said moistening device. 15
14. Apparatus for printing records from a copyable mirror-script original onto a paper sheet comprising a printing drum bearing copyable mirror-script original, a counter pressure roller co-operating with said drum, means for passing a continuous paper sheet between said drum and said roller, automatic cutting means including a displaceable stationary knife and a plurality of rotatable knives for said paper sheet, a moistening device for moistening said paper sheet with a rapidly volatilizing solvent, a tank for said solvent connected to said moistening device, and a control valve between said tank and said device for periodically and automatically releasing solvent from said tank to said moistening device. 20
15. In a duplicating apparatus printing from a copyable mirror-script original onto a continuous strip of paper previously moistened with a rapidly volatilizing solvent, the combination comprising a printing drum bearing copyable mirror-script original, a counter pressure roller co-operating with said printing drum, means for passing a continuous paper strip moistened with a rapidly volatilizing solvent between said drum and said roller, a displaceable stationary knife having operative and inoperative positions, and a rotatable knife adapted to co-operate with said stationary knife in the operative position thereof to cut said paper strip into individual 25 sheets. 30
16. In a duplicating apparatus printing from a copyable mirror-script original onto a continuous strip of paper previously moistened with a rapidly volatilizing solvent, the combination comprising a printing drum bearing copyable mirror-script original, a counter pressure roller co-operating with said printing drum, means for passing a continuous paper strip moistened with a rapidly volatilizing solvent between said drum and said roller, a displaceable stationary knife having operative and inoperative positions, at least one rotatable knife adapted to co-operate with said stationary knife in the operative position thereof to cut said paper strip into individual sheets, means for rotating said printing drum, and means for rotating said rotatable knife in dependence on the rotation of said printing drum. 40

WILHELM RITTERFELD.
